AGITATOR FOR GAME ELEMENTS

Charles F. Klein, Baltimore, Md.

Application February 11, 1937, Serial No. 125,318

6 Claims. (Cl. 273—145)

The present invention relates to games and the like, and has more particular reference to an agitator for game element or the like adapted to be used in connection with the playing of a game.

5 An object of the present invention is to provide an agitator which holds a game element in full view at all times of the players and which will efficiently roll or turn over the game element in different directions so that there is an 10 equal chance of any of the faces of the game element to be exposed uppermost upon the operation of the agitator, and to provide an agitator which is of the spinning type but which also is so constructed and supported that it may move, 15 flex or vibrate universally at practically all directions so that it is practically impossible for a player to control the tumbling of the game element in the agitator.

Another object of the invention is to provide 20 a simplified construction which may be economically manufactured and sold, which is relatively small and compact so that it may be transported and packed either separately or as a part of a game board or the like, and a device which can- 25 not easily get out of order.

With the foregoing and other objects in view, the invention will be more fully described herein- 30 after, and will be more particularly pointed out in the claims appended hereto.

35 In the drawing, wherein like symbols refer to like or corresponding parts throughout the several views,

Figure 1 is a top plan view of a game element agitator constructed according to the present in- 40 vention.

Figure 2 is a vertical section taken through the same, on the line 2—2 of Figure 1.

Figure 3 is a detail fragmentary enlarged outer face view of one of the shaft section mountings, 45 the shaft being shown in section.

Figure 4 is a vertical sectional view taken through the shaft section mounting, and

Figure 5 is a detail enlarged side elevation of a game element which may be used with the 50 agitator.

Referring now to the drawing, the agitator comprises a body part 10 preferably in the form of a transparent globe of glass or the like and in which is adapted to be placed a game element 11, although a plurality of game elements may be placed therein if desired.

The globe 10 is preferably open at opposite sides and is closed and supported at each open side by an outer large disc 12 provided with a 55 cushioning flexible disc 13 at its inner side and

against which the marginal edge of the globe opening is adapted to seat, and by a small disc 14 which engages against the flexible disc 13 to hold it in place. The discs 12 and 14 may be of metal while the interposed cushioning disc 13 may be of rubber, felt or the like. This structure prevails at each side of the globe 10 and the discs 12 and 14 are firmly mounted upon alined transverse rods or shaft sections 15 providing trunnions, so that by turning the shaft sections the 10 transparent globe 10 is spun therewith. If desired, a plurality of bails or wires 16 may extend about the sides of the globe 10 and secured at their ends to the outer discs 12 to serve as a protection for the globe 10 and also to firmly hold 15 the discs or heads against the opposite sides of the globe.

The shaft sections 15 are supported in a fork 16' or the like which has its free ends extending upwardly and laterally enlarged to accommodate 20 the shaft sections 15. The upper ends of the fork 16 are provided with curved or arcuate slots 17 which extend in a general horizontal direction and which are of sufficient width to accommodate grooved wheels or pulleys 18 having a loose 25 fit between the opposed marginal edges of the slots 17 so that the upper ends of the fork hold the pulleys 18 from displacement but at the same time admit of the relatively free turning or rolling 30 of the pulleys on the lower edges of the slots 17. The opposite shaft sections 15 extend axially through the pulleys 18 and are mounted in the pulleys upon ball bearings 19 or the like so that the shaft sections 15 may turn easily and freely 35 within the pulleys independently of any rolling 35 action of the pulleys.

The fork 16' is provided at its lower end with a depending stem 20 to which is secured the upper end of a supporting spring 21, and the lower end of the spring 21 is connected to a lower stem 40 or stud 22 which carries, in fixed relation thereto, a supporting disc 23 which rests upon ball bearings 24 mounted in a depressed seat 25 provided in the upper portion of a supporting base 26. The stud 22 extends downwardly from its disc 23 45 through the seat 25 and is loosely secured through the seat by lock nuts 27 or the like. The stud 22 may thus freely rotate on the base 26, the spring 21 is free to flex laterally in all directions and also capable of vertical compression and expansion 50 so that the fork 16' is supported yieldingly in upright position and for easy turning upon the base 26.

The opposite shaft sections 15 are provided with milled thumb pieces 28, or the like, adapted 55

to be grasped, either one or both, for spinning the same and the transparent globe 10. The pressure or operation of spinning not only sets the shaft sections 15 with the globe 10 in operation, 5 but also disturbs, rocks and rotates the fork 16', and also causes the pulleys or wheels 18 to move or roll in the slots 17. The globe 10, therefore, not only spins but moves about a vertical axis and also moves in and out of the vertical axis of the 10 fork and consequently sets up various lateral and turning movements to the game element 11 which is enclosed within the globe 10.

While any suitable type of game or indicating element may be used in the hollow body portion 10, there is shown particularly in Figure 5, a game element having a desired number of flat faces 29 bearing suitable numbers or other indicia, and which may be 14 in number so as to permit the somewhat easily rolling of the game element 20 11 when the body portion 10 is rotated on either a horizontal or vertical axis, or when the hollow body 10 is oscillated upon the spring 21 or upon its bearing rollers or pulleys 18.

In operation, the shaft sections 15 are twirled 25 between the fingers so as to rotate the shaft sections with the heads and the transparent globe 10. The globe 10 is thus set in motion, and the pressure exerted upon the shaft sections 15, through the thumb pieces 28, is such as to move 30 the rollers or pulleys 18 in the slots 17 so that the shaft sections are rocked or oscillated back and forth within the limits of the slots 17 upon the support during the rotation of the globe 10. Also, the side pressure exerted upon the shaft 35 sections 15, in the act of twirling, causes the support 16' to oscillate or swing upon the spring 21 so that the globe, while spinning, is thus subjected to various movements at different angles and planes to one another. The support 16' is 40 also turned to a more or less extent upon the base 26 as the disc 23 is freely supported upon the bearings 24. These different movements of the rotating body portion 10 impart various directional impulses to the tumbling game or indicating element 11 and consequently the die is turned 45 over upon different sides and is not held to any particular plane of rotation. In this manner the game element 11 is thoroughly agitated and the element of chance of different faces 29 turning up, when the game element finally comes to rest, 50 is enhanced.

This device is adapted to take the place of cups, receptacles or the like in which game elements have to be placed after they have been 55 thrown, and eliminates the tiresome operations of collecting the game elements and placing them in the cup for each successive throw.

As the lower walls or edges of the slots 17 are curved upwardly toward the ends of the slots, the 60 pulleys or rollers 18 gradually come to rest at the intermediate portions of the slots 17, the shaft 15 is free to turn upon its bearings 19 in the rollers or pulleys 18 independently of the oscillating movement of the rollers or pulleys.

It is obvious that various changes and modifications may be made in the details of construction and design of the above specifically described embodiment of this invention without departing from the spirit thereof, such changes and 65 modifications being restricted only by the scope of the following claims:

What is claimed is:

1. A game element agitator, comprising a

transparent body portion adapted to enclose a game element, a support horizontally and pivotally connected to the body portion to admit rotation of the latter to roll the game element therein, a base, and a spring stem rotatably mounted 5 between the support and the base for admitting rotation and oscillation of the support on the base for changing the direction of rolling of the game element in the body portion as the latter is rotated.

2. A game element agitator, comprising a transparent globe adapted to receive a game element therein and having opposed openings in its lateral portions, transverse shaft sections extending for the transparent globe and having heads thereon engaging the globe to support the same for rotation with the shaft sections, a fork, bearings mounted in the fork engaging the shaft sections to support the globe for rotation in the fork, a base, and a flexible and rotatable connection between the base and the fork for turning the latter at right angles to the axis of the shaft to vary the direction of rotation of the game element in the globe as the latter is turned.

3. A game element agitator comprising a transparent globe adapted to receive a game element therein, horizontal shaft sections secured through the globe, a fork, said fork having upturned ends with horizontal slots therein curved 20 upwardly at their opposite ends, pulleys fitted in 30 said slots adapted to bear upon the lower edges of the slots, bearings between said pulleys and the shaft sections for rotatably mounting the shaft sections in the pulleys for turning independently 35 of the rolling of the pulleys in the slots, and a flexible and rotatable supporting means for said fork.

4. A game element agitator comprising a fork, transverse shaft sections extending through 40 the fork, and a transparent globe mounted in the fork on said shaft sections and adapted to receive a game element therein, rollers mounted in said fork for movement transversely thereof and having axial bearings engaging said shaft sections to support the shaft in said rollers and 45 admit rotation of the shaft sections independently of the transverse movement of the rollers, and means for supporting the fork.

5. A game element agitator comprising a fork, supporting means for said fork, a transparent globe disposed between the arms of said fork and adapted to receive a game element, shaft means engaging the globe and the arms of the fork to rotatably mount the globe on the fork, said shaft means having an extension laterally of at least one arm of said fork, a spinning knob on said shaft extension, rollers mounted in 55 said fork for movement transversely thereof and having axial bearings engaging said shaft means to support the shaft means in said rollers and 60 admit rotation of the shaft means independently of the transverse movement of the rollers.

6. A game device, comprising a hollow spherical body portion, the walls of said body portion being transparent, a game element of generally 65 spherical shape having a plurality of facets, said element being located within said body portion, and means for mounting said body portion for rotation to agitate said element, said game element adapted in its rest position to rest on a 70 facet at the lowermost point of said body portion.

CHARLES F. KLEIN.
